UNITED STATES PATENT OFFICE

CHARLES E. RAYMOND, OF BOSTON, MASSACHUSETTS

SUCTION DEVICE

Application filed September 14, 1929. Serial No. 392,641.

This invention relates to a novel suction device for attachment to an engine piston for the purpose of jerking the piston in its cylinder, to ascertain whether there is any looseness of the wrist-pin, crank-pin or crank-shaft bearings, or any lateral play of the piston in its cylinder.

The invention will be best understood by reference to the following description, when taken in connection with the accompanying drawings of one specific embodiment thereof, while its scope will be more particularly pointed out in the appended claims.

In the drawings:—
15 Fig. 1 is a central, longitudinal, sectional view of a suction device embodying the invention; and

Fig. 2 is a sectional view of a portion of an engine with the suction device attached to the 20 piston in readiness for conducting a test.

Referring to the drawings, and to the embodiment of the invention which is illustrated therein, there is shown a suction device comprising means presenting a chamber 3, having a variable air capacity, and an opening 4 leading into said chamber. In the embodiment illustrated in the drawings, the chamber is formed by a cylinder 5, having a piston 6 working therein. The cylinder has at one 25 end a cylinder head 7, presenting a piston-rod guide 8, loosely fitted to allow the escape of air between the rod and the guide and at its other end a cylinder head 9 presenting a pad 10, herein comprising a body of resilient material 11, such as soft rubber, and provided with a slight concavity 12 in its work face. To prevent deformation of the pad when subjected to the action of manipulating an object to which the pad is attached by the suction of the device, the pad has suitable provision, herein metallic reinforcing means, which as shown in the drawings comprises a lateral flange 13, formed on the cylinder head 9 and provided with a plurality of openings 14, through which the rubber flows when being molded on and about the flange. This reinforcing means incorporated in the pad lends thereto a sufficient rigidity to prevent deformation of the pad, while still taking advantage of the resiliency of the rubber to

obtain a firm adhesion of the pad to the top of the engine piston. A perfect seal to prevent subsequent leakage of air into the chamber may be obtained by wetting the slightly concave surface 12 with water, just prior to 55 the application of the pad to the engine piston. In the example shown, the cylinder head 9 is conveniently secured to the cylinder by a screw-thread 15. The other cylinder head 7 need not be secured to the cylinder, 60 but is provided with a laterally projecting flange 16, resting upon the adjacent end of the cylinder to prevent the cylinder head from moving inwardly beyond its proper position.

The piston 6 is provided with suitable means, herein a cupped leather washer 17, and an expanding spring ring 18, to prevent leakage of air from the upper portion of the cylinder into the chamber 3. Herein, the leather washer is clamped in place on the piston by a nut 19, screwed onto a boss 20 presented by the piston, and this nut is provided with a circumferential groove 21, to receive the 65 spring ring.

By moving the piston toward the opening 4, the size of the chamber is reduced, and air is expelled therefrom. The working face of the suction device is then applied to the object to be manipulated, and the piston 6 is 70 now moved in the opposite direction (herein upwardly), to increase the capacity of the chamber 3, thereby creating a powerful suction which causes adhesion of the pad to the object. Herein, the piston is elevated by means of a piston rod 22, which extends upwardly over the piston-rod guide 8, and is provided with an appropriate handle 23. The tendency of the piston when thus elevated to descend is resisted by suitable means, 75 herein a helically-coiled spring 24, which is closely wound, that is to say, its coils normally touch one another,—but it can be stretched by a downward thrust on the piston rod. This, of course, make it necessary to attach the ends of the spring to the piston 6 and to the cylinder head 7, respectively. This is conveniently accomplished in the present example by providing the boss 20 with threads 25, onto which several turns of 80

the lower end of the spring are screwed, while the upper end of the spring is secured to the upper cylinder head in a similar manner, by providing the cylinder head with a boss 26 threaded to receive several turns of the upper end of the spring. To prevent any possible injury to the spring which would result from rotation of the piston by the piston rod, the latter is attached to the former by a swivel connection, herein conveniently made by providing the boss 20 with a cylindrical bore 27, which loosely receives a head 28 presented by the lower end of the piston rod. After the head has been inserted, the upper end of the boss is flanged inwardly, as at 29, about a neck 30 presented by the piston rod. If, now, the user should rotate the piston-rod, the piston is not thereby rotated, and no injury to the spring can result.

In Fig. 1, the spring is shown elongated, or stretched from its normal, closed position by the downward thrust of the piston rod. This is accomplished by placing the pad on the object to be manipulated, and then pushing the piston rod downwardly to expel air from the chamber 3 through the opening 4, and outwardly along the concave surface 12, which is against the object. The pressure of the hand is then removed from the handle 23, and the spring, being no longer restrained, exerts an upward pull on the piston and elevates the latter. Usually, the piston will rise several inches in the cylinder, but the latter is made long enough and the spring is made of such length that the piston could ascend still further under the influence of the spring, were it not for the reduction of the air pressure in the suction chamber 3. In other words, the spring from then on constantly tends to increase the size of the suction chamber, and thereby to rarefy the air in the chamber. The suction is so powerful that tremendous pressure would be required to detach the device from the object by exerting an upward pull on the cylinder.

In Fig. 2, there is shown a portion of an engine comprising a cylinder 31, having a piston 32 working therein, and connected to a crank-pin 33 by a connecting rod 34 and a wrist-pin 35. To test the engine for possible looseness, the suction device is applied to the upper face of the engine piston in the described manner, and the cylinder 5 of the suction device is then firmly grasped by the hand or hands of the user. By attempting to jerk the piston up and down, any undue looseness in the bearings can be felt instantly, and the necessary adjustment can be made, by removal of the lower part of the engine crank-case. If there is no undue play, removal of the lower part of the crank-case is unnecessary, and much labor and expense are avoided. The device can also be used for testing the piston for looseness in the cylinder, by attempting to jerk the piston laterally.

Having thus described one embodiment of the invention, but without limiting myself thereto, what I claim and desire by Letters Patent to secure is:—

1. In a suction device, the combination of a cylinder having at one end a cylinder head presenting a piston-rod guide and at the other end a cylinder head presenting a pad and having an opening communicating with the interior of said cylinder, a piston working in said cylinder, a piston-rod extending through said guide, and a spring yieldingly resisting movement of said piston toward the second-mentioned cylinder head. 70

2. In a suction device, the combination of a cylinder having at one end a cylinder head presenting a piston-rod guide and at the other end a cylinder head presenting a pad and having an opening communicating with the interior of said cylinder, a piston working in said cylinder, a piston-rod extending through said guide, and a spring attached at one end to the first-mentioned cylinder head and at the other end to said piston and yieldingly resisting movement of said piston toward the second-mentioned cylinder head. 80

3. In a suction device, the combination of a cylinder having at one end a cylinder head presenting a piston-rod guide and a threaded boss and at the other end a cylinder head presenting a pad and having an opening communicating with the interior of said cylinder, a piston working in said cylinder and presenting a threaded boss, a piston rod extending through said guide, and a helically-coiled spring about said piston rod and having at its ends turns which are screwed onto the threads of said bosses, said spring yieldingly resisting movement of said piston toward the second-mentioned cylinder head. 90

4. In a suction device, the combination of a cylinder having at one end a cylinder head presenting a piston-rod guide and a threaded boss and at the other end a cylinder head presenting a pad and having an opening communicating with the interior of said cylinder, a piston working in said cylinder and presenting a threaded boss, a piston rod having swivelled connection with said piston extending through said guide, and a helically coiled spring about said piston rod and having at its ends turns which are screwed onto the threads of said bosses, said spring yieldingly resisting movement of said piston toward the second-mentioned cylinder head. 100

5. In a suction device the combination of a cylinder having at one end a relatively thin and internally reenforced pad, said pad being of relatively large area in comparison to said cylinder and having an opening communicating with the interior of said cylinder, a piston working in said cylinder, and resilient means resisting the movement of said piston toward the opening. 110

6. In a suction device, the combination of a

cylinder having at one end a pad having an opening communicating with the interior of said cylinder, a piston bodily slideable in said cylinder, said piston having a swivel connection with its piston head, and resilient means for resisting the movement of said piston toward said opening.

7. In a suction device, the combination of means presenting an expandible and contractible chamber, a relatively thin and internally reenforced pad of relatively large area, said pad having an opening leading into said chamber, the contact surface of said pad having a slight permanent concavity, which when applied to the surface of an object affords a sustaining contact surface adapted to be flexed downwardly so that said contact surface is substantially coextensive with the area of the pad.

20 In testimony whereof, I have signed my name to this specification.

CHARLES E. RAYMOND.
